OUTLET FOR MILK DELIVERY CANS

John A. Hopwood, Westfield, N. J., assignor to
 Monitor Process Corporation, Jersey City, N. J.,
 a corporation of New Jersey

Application March 7, 1950, Serial No. 148,063

1 Claim. (Cl. 220—66)

1

This invention is an outlet for milk delivery cans of the general character disclosed in my prior Patent No. 2,282,836. This patent discloses a can from which milk may be dispensed through a discharge tube extending through the side wall of the can near the bottom thereof. The tube is slidable into and out of the can through a leak proof gasket carried by a sheet metal cup permanently attached to the side wall of the can and projecting into the confines of the can.

The structure shown in this patent operates with high efficiency and is acceptable to the Boards of Health of most places. In certain localities, however, the Board of Health regulations require that the interior of the can must be absolutely flush throughout and the can of my said prior patent will manifestly not conform with this regulation because of the protrusion of the cup into the interior of the can.

The present invention overcomes this objection by so arranging the cup that its inner end is flush with the inner surface of the side wall of the can and at the same time the cup is adequately supported on the wall of the can against the hard wear and tear to which milk cans are subjected in use. These cans may be made initially to embody the present invention, but it is generally found desirable to produce them by conversion of conventional milk delivery cans of the twenty or forty quart variety into side delivery cans embodying this invention. This invention includes a novel method of accomplishing the conversion of such a conventional can.

Features of the invention, other than those adverted to, will be apparent from the herein-after detailed description and appended claim, when read in conjunction with the accompanying drawings.

The accompanying drawing illustrates one practical embodiment of the invention, but the construction therein shown is to be understood as illustrative, only, and not as defining the limits of the invention.

Figures 1-6, inclusive, are fragmental perspective sections showing consecutive steps in the method of modifying a conventional milk delivery can to permit it to be used as a side delivery can as stated.

Figure 7 is a face view of a cup supporting boss shown as secured to the can in several of the preceding figures.

Figure 8 is a section on the line 8—8 of Figure 7.

Figure 9 is a bottom view of a reinforcing plate shown in the form of a sheet metal stamping

2

adapted to be secured to the bottom wall of the can in the region of the outlet opening.

In the accompanying drawing, 1 designates the side wall of a conventional milk delivery can. This wall is of cylindrical form and is provided at its top with the usual breast above which projects the neck of the can, surmounted by a lip. A can of this general character is shown in William Tamminga Patent No. 2,186,082. The can has a closed bottom 2 which is dished downwardly from its periphery and the lower portion of the periphery of the side wall of the can is commonly embraced by a reinforcing ring 3 welded or otherwise permanently secured to said side wall.

In Figures 1-6 of the drawing a conventional form of can is shown wherein the bottom is formed integral with the side walls. In some cases, the bottom is formed separately and is provided with a depending flange permanently fixed to the side walls. In other cases, the side wall extends to the very bottom of the can and a reinforcing ring is positioned inside of the side wall and below the can bottom. These, however, are details of construction relating generally to the different ways in which conventional cans are made and it is to be understood that the present invention may be associated with any known form of conventional can.

In carrying out the method of this invention with a can as shown, a short arcuate slit 4 is first made along a line where the bottom 2 joins the side wall 1, as indicated in Figure 1. This slit extends entirely through the bottom of the can and follows the plane of the side wall 1. After the slit has been made, that portion of the bottom of the can between the termini of the arcuate slit is pressed downwardly to form a channel 5 of arcuate cross section, as shown in Figure 2. This channel, of gutter, as it is sometimes called, extends from substantially the center of the can and the bottom of the channel lies substantially in the plane of the lowest portion of the can bottom, so that milk may drain through said channel from the center of the bottom 2.

After the channel has been formed as stated, a hole 7 is cut through the side wall of the can and through the reinforcing ring 6 which is shown as permanently secured to the exterior of the side wall. This hole 7 substantially registers with the channel 5, but is sufficiently large to receive the base of the cup 8. Figure 3 shows the relation of the opening 7 to the channel 5.

There is next affixed to the exterior surface of

the ring 6 a boss 9 shown in detail in Figures 7 and 8. This boss is of annular form and its central opening 10 is shaped to receive the cup in snug close fitting relation. The peripheral edges of the boss are preferably sloped, as shown at 11, and this sloping may extend entirely around the boss if desired, so that, when the boss is in place on the can, objects striking the boss will slide off of the same rather than tend to dislodge the boss from the can.

The boss is secured to the can by the step shown in Figure 4, the central opening 10 being brought into registration with the opening 7 in the side of the can and the boss thereupon welded, soldered or otherwise permanently mounted coaxially of said opening 7. I preferably also secure the boss to the can by rivets 12 which pass through rivet holes 13 formed in the boss and through aligned holes in the ring 6. The purpose of these rivets is to assist the solder, weld or other attachment in permanently securing the boss in place, so that it cannot be knocked off if struck by or against some extraneous object.

The thickness of the boss is such that, when applied to the can, as shown in Figure 4, and the cup 3 introduced, as shown in Figure 5, the outer flange 14 of the cup will seat against the outer surface of the boss while the flange 15 at the inner end or base of the cup will be flush with the inner surface of the side wall 1 of the can. The cup is secured in this position by welding or soldering it permanently in place and in this soldering operation, solder is flowed into the joint between the inner portion of the cup and the side wall and bottom of the can so as to form a liquid tight joint therewith.

Having thus applied the boss and cup and firmly and permanently secured them in place, I next apply to the under surface of the bottom of the can a reinforcing plate 16, shown in Figure 9. This plate is stamped from sheet metal, so as to conform to the bottom of the can and the channel 5 thereof and to underlie said channel when in place on the can. The reinforcing plate may be conveniently secured in position by sweating it or soldering it in place. It serves to render the channeled portion of the can very rigid and it protects said channel against damage in the event that the can is set upon an uneven surface or some upwardly protruding object, such as a stone or the like.

When the can is thus completed, the inner surface of the cup will be flush with the inner surface of the side wall and no part of the cup will protrude into the interior of the can. This can meets all the requirements of those localities

where a flush interior can is required and it provides adequate mounting for the cup and effectual protection against damage of any of the parts even when the can is subjected to hard usage.

5 The annular cup supporting boss which I have shown in the drawings is made solid and this I prefer, although it may be cored or stamped from sheet metal without departing from the invention. Furthermore this boss is shown as substantially equal in height to the height of the reinforcing ring 6, although, in practice, it may extend above this ring and the top of the boss may have a greater slope than as shown if this is desired. For these reasons and others, the invention is to be understood as fully commensurate with the appended claim.

Having thus fully described the invention, what I claim as new and desire to secure by Letters Patent is:

20 A single walled milk delivery can having a side wall with a reinforcing ring embracing its lower margin and a dished bottom with a channel leading from substantially the center of the can to the periphery of the bottom and there substantially registering with an outlet opening in the side wall of the can and through the reinforcing ring, a boss welded onto the exterior of the reinforcing ring and having an opening registering with the outlet opening in said ring and in the side wall of the can, and a discharge tube cup seated in and welded to said boss with the inner end of said cup provided with a cross-axial internal flange positioned flush with the inner surface of the side wall of the can.

35 JOHN A. HOPWOOD.
